AUTOMATIC GUN

Antonin Podrabsky, Brunn, Czechoslovakia, assignor to Czechoslovenska Zbrojovka Akciová Společnost V. Brne, Brunn, Czechoslovakia

Application September 24, 1932, Serial No. 634,651, and in Czechoslovakia October 21, 1931

15 Claims.

(Cl. 42—4)

The present invention relates to an automatic gun in which fixing means are provided which enable a catch, forming part of the firing mechanism, arranged for displacement in the path of movement of the breech block mechanism and adapted to co-operate therewith, to be fixed without actuation of the trigger of the gun.

According to a further feature of the invention, instead of the catch member only, the whole firing mechanism may be capable of adjustment and fixing relative to the breech block. The displaceable arrangement and fixing of the catch member or the firing mechanism by fixing means affords certain advantages, particularly from the standpoint of the simplified construction of the gun and the raising of its reliability during operation. In particular it is possible for this reason to mount the catch member or the firing mechanism on a carrying member mounted for sliding movement longitudinally of the gun and to construct this carrying member, in addition, as the carrying member for the cocking mechanism or as the cover for the cartridge ejector opening, or finally both as carrier for the cocking mechanism and also as cover for the cartridge ejector opening. Thus not only is the construction of the gun considerably simplified and its reliability during operation increased but, in particular, openings in the gun casing are dispensed with which would be necessary if the firing mechanism, cocking mechanism and cartridge ejector cover of the gun were arranged separately on it.

In the accompanying drawings is shown an automatic gun as a constructional example of the invention, in which the firing mechanism, the cocking mechanism and the cover for the cartridge ejector opening are on one common carrying member.

Fig. 1 shows the gun in the inoperative position in partial longitudinal section.

Fig. 2 shows the gun with the breech block cocked, also in partial longitudinal section.

Figs. 3 and 4 show in elevation the rear part of the gun.

Fig. 5 shows in longitudinal section a carrying member with integral firing mechanism.

Fig. 6 shows a side elevation of the carrying member.

In Fig. 7 is shown a section on the line VII—VII of Fig. 5, looking from left to right; in this figure the switch-over member for firing single shots and for continuous fire is removed from its place.

Fig. 8 shows a plan view of Fig. 5 or Fig. 6.

Figs. 9 and 10 show details of the firing mechanism in the locked position.

Figs. 11 and 12 show the same details during continuous fire, and

Figs. 13 and 14 the same parts when firing 60 single shots.

In the constructional example shown in the drawings the breech block mechanism is designated by *x*. The arrangement of the breech block is unimportant so far as the present invention is concerned. The present invention is applicable to guns of all kinds no matter how the breech block obtains its movement. As a constructional example of the invention a gun is chosen for the drawings which has a breech block carrier 1 and a breech block 2 adapted to reciprocate towards and away from the breech block carrier. The actuation of the breech block carrier may be effected either by means of a gas piston working in a gas pressure cylinder or by means of a lever arrangement operated upon discharge or by similar means. The breech block carrier is mounted in suitable guides for sliding in a direction longitudinal of the gun, so that the under surface 4 of the breech block carrier travels along the path of movement A—A. 3 is the barrel of the gun, 5 is a casing attached to the barrel and 6 is a fixed casing which encloses the whole breech block mechanism *x*. The most important part of the firing mechanism *y* of the gun is the catch 10 which co-operates with a part of the breech block mechanism, in the example shown, with the breech block carrier 1.

According to the invention this catch 10 can be displaced parallel to the path of movement A—A and can be retained in the displaced position. In Figs. 1 and 2 are shown both characteristic positions of the catch 10. In Fig. 1 the catch is in the position of rest. Fig. 2 shows the catch 10 when the breech block has been cocked. The displaceable catch can be coupled in any way with any desired construction of firing mechanism *y*. In the present constructional example the whole firing mechanism is displaceable with the catch 10, and it is for this very purpose that the firing mechanism *y* is mounted on a carrying-member 15, which is slidably arranged by means of guide-bars 16 in guide-grooves 17. The guide-grooves 17 run parallel to the plane of movement A—A.

On the carrying-member 15 near the firing mechanism *y* is also arranged the cocking mechanism 2; this consists of a handle 20 which is pivotally mounted in an arm 21 of the carrying member 15. 23 and 24 are notches which allow

the position of the handle 20 to be fixed. In Fig. 3 the handle is in the position ready for use. Fig. 4 shows the handle in the position for carrying the gun.

5 The catch 10 is common to the firing mechanism *y* and the cocking mechanism *z*, and it engages from below in the notch 11 of the breech block carrier 1. First of all the breech block can be cocked by means of the catch 10 and the 10 cocking mechanism *z* (Fig. 2). But the catch also allows the gun both to fire shots singly and to fire continuously since it forms an integral part of the firing mechanism.

The firing mechanism *y* consists, in the constructional example shown, of the trigger 30 which has the form of a push button slidably carried in guides 31 in the carrying member 15. The trigger button 30 is arranged at the rear end of the carrying member 15 and is mounted on 20 a control member 32 whose end 33 co-operates with the catch 10. The catch 10 consists of a bell-crank lever rotatable about the pivot pin 35, one arm of which constitutes the catch 10, while the other arm has a step-shaped recess 36 25 on one side of which is provided an abutment 37 in the form of a projection. The control member 32 co-operates with the switch-over member 40 for firing single shots and for continuous fire. The switch-over member 40 consists of a pin, 30 which is carried in holes in the side walls of the carrying member and extends across the hollow interior of the carrying member. 41 is a hand lever for actuating the switch-over pin 40.

The switch-over pin is of rectangular cross section and is provided with recesses 42, 43 which, as explained later, co-operates with a pin 44 and an abutment 45 on the control member 32. On the latter is provided a spring casing 47 which encloses a spring loaded pin 48. The head 49 of 40 the spring loaded pin is interchangeably inserted in an opening 50 in the floor of the carrying member. The pin 48 extends forward at an inclination, so that both horizontal and vertical movements of the control member 32 are spring-controlled by the spring 52, whose rear end presses 45 against the rear wall of the spring casing 47.

In order to be able to fix the carrying member, particularly in the cocked position (Fig. 2), the said member is provided with fixing means. 50 These consist of a fastening catch 60 which is rotatably mounted at 61 on the carrying member and has an operating arm 63, which is located on the underneath of the carrying member. 64 is a spring which resiliently urges the fastening 55 catch 60 into the fixing position. The fastening catch 60 co-operates with a fixed abutment 67 on the gun. This fixed abutment is for example provided in the casing 6. The latter is also provided with an abutment 68 which limits the rearward movement of the carrying member and against which the carrying member abuts when in the cocked position (Fig. 2).

As is clear from Figs. 3, 4 and 8 the handle 20, 65 the press button 30 and the operating lever 63 are arranged in the rear part of the carrying member 15. They are thus so disposed that when the handle 20 is grasped the press button 30 can be pressed with the thumb of the same hand. 70 The operating lever 63 is likewise so arranged relative to the handle 20 that when the handle is grasped the lever 63 can also be actuated with the thumb. On the other hand, when the parts 75 20, 30 and 63 are disposed relative to one another as described above, it is not possible when gripping the handle 20 to actuate both the press button 30

and the lever 63 simultaneously, a fact which very considerably increases the safety of the gun.

The carrying member 15 also constitutes the cover for the cartridge-ejector-opening 70. The cartridge-ejector-opening 70 is formed by the opening which is necessary for the sliding of the carrying member 15. In the inoperative position the carrying member 15 closes the cartridge-ejector-opening as is shown in Fig. 1. In the cocked position (Fig. 2) the cartridge ejector opening is uncovered by the carrying member 15. Additional covers may obviously be provided, which in the inoperative position (Fig. 1) close the rear part of the guide opening for the carrying member. These additional covers could for instance consist of telescopic plates slidable one over the other.

Cocking of the gun takes place when the handle 20 is first turned to the position shown in Fig. 3 and is then, by grasping the handle of the carrying member 15, moved from the position shown in Fig. 1 to the position shown in Fig. 2. The catch 10, owing to its engagement in the recess 11, takes the breech block carrier 1 with it and cocks the breech block. The movement of the carrying member 15 is limited in the rearward direction by the projection 68. The fastening catch 60 snaps behind the abutment 67 and holds the carrying member 15 fast.

The firing mechanism is operated by pressing 105 the trigger button 30. When the abutment pin 40 occupies the position shown in Fig. 10 then the firing mechanism is locked. The press button 30 together with the control member 32 can only be moved a very small amount, since the 110 rectangular cross sectioned switch-over pin 40 occupies its horizontal position (Fig. 10); therefore the abutment 45 after a small movement strikes against the narrow side 40' of the switch-over pin and so further actuation of the firing 115 mechanism is prevented. When the switch-over member takes up the position shown in Fig. 12, continuous fire is permitted. When the trigger is pressed the abutment 45 lies against the surface 40'' of the switch-over pin which now has 120 its long side vertical. In this position the parts 33, 36 and 37 of the released control mechanism occupy the position shown in Fig. 11. In order that the gun may be made manifestly safe in this position also, the safety pin 44 is provided 125 which, on pressing the trigger comes to rest above the upper surface of the switch-over member and thereby prevents the descent of the control member 32 together with its end 33. In the position for continuous fire the catch 10 is with- 130 drawn from the breech block as long as the trigger button 30 is pressed. When the trigger button 30 is released the whole firing mechanism returns to the inoperative position in which the catch 135 engages and holds the breech block carrier.

When the switch-over member is in the position shown in Fig. 14 the gun is adjusted for firing single shots. In this position the press button 30 can be moved to the fullest extent, since in this position the abutment 45 is opposite 140 the recess 43. When the press button is pressed the abutment 45 enters the recess 43, the end 33 of the control member 32 is moved so far to the left that 33 comes out of engagement with 145 37 and the catch 10, owing to the spring controlling it snaps back into the position of engagement (Fig. 13). As it snaps back the end 33 is pressed downwards and this causes the control member 32 to be swung slightly downwards. This downward swinging is not prevented 150

5 by the safety pin 44 since the recess 42 is in the path of rotation of the pin 44 when the switch-over member is in the position shown in Fig. 14 (see also the switch-over member in the same position in Figs. 5 and 8). When the switch-over member is in the position shown in Fig. 14 the catch 10 jumps back into the retaining position as soon as the trigger button 30 has been actuated, so that the breech block 10 is directly held in the cocked position. Thus firing of single shots is permitted.

10 The handle 20 serves firstly to cock the breech block. But since the carrying member, when in the cocked position, is held fast, relatively to the gun, against all relative movements, the whole gun can therefore also be aimed by means of the handle 20.

15 Though the above described firing mechanism, on account of its exceptional simplicity and the fact that it is constructed of very few parts is particularly suited for housing in the carrying member 15, yet the invention is not limited to the construction of firing mechanism described. The same also applies to the other parts of the gun according to the present invention, which can be altered with regard to their arrangement and constructional form within the scope of the present invention. The only important point is that the catch in the firing mechanism, which 20 co-operates with the breech block can at any rate be so adjusted and so fixed with regard to the breech block that the said catch when in the adjusted position can fully carry out the function it is called upon to perform.

30 I claim:

1. An automatic firearm comprising a barrel, a breech casing, a breech block moving mechanism adapted to make sliding movements within the breech casing, firing mechanism including a trigger, a catch mounted on the firing mechanism and adapted to co-operate with the breech block moving mechanism, means on the firing mechanism whereby the latter is moved together with the breech block moving mechanism to cock the gun and fixing means whereby the firing mechanism and breech block moving mechanism are held in the cocked position without operation of the trigger.

40 2. An automatic firearm comprising a barrel, a breech casing, a breech block moving mechanism adapted to make sliding movements within the breech casing, firing mechanism including a trigger, a catch mounted on the firing mechanism and adapted to co-operate with the breech block moving mechanism, a handle pivotally mounted on one side and towards the rear of the firing mechanism whereby the latter is moved together with the breech block moving mechanism to cock the gun and fixing means whereby the firing mechanism and breech block moving mechanism are held in the cocked position without operation of the trigger.

45 3. An automatic firearm comprising a barrel, a breech casing, a breech block moving mechanism adapted to make sliding movements within the breech casing, a sliding carrier, firing mechanism mounted on the sliding carrier, a catch on the sliding carrier adapted to co-operate with the breech block moving mechanism to determine the position of the latter with regard to the sliding carrier, a handle on the sliding carrier operable to cock the gun, a trigger mounted on the sliding carrier in a position where it can be operated by the thumb of a hand grasping the cocking handle and fixing means whereby

the catch is held in a desired position without operation of the trigger.

50 4. An automatic firearm comprising a barrel, a breech casing, a breech block moving mechanism adapted to make sliding movements within the breech casing, a sliding carrier, firing mechanism mounted on the sliding carrier, a catch on the sliding carrier adapted to co-operate with the breech block moving mechanism to determine the position of the latter with regard to the sliding carrier, a handle on the sliding carrier operable to cock the gun, a trigger mounted on the sliding carrier in a position where it can be operated by the thumb of a hand grasping the cocking handle, a pivoted latch carried on the sliding carrier and a fixed stop co-operating with said latch to hold the catch in a desired position without operation of the trigger and a handle on the sliding carrier for releasing the latch from the fixed stop and arranged in a position where it is operable by the thumb of a hand grasping the cocking handle.

55 5. An automatic firearm comprising a movable breech block mechanism, firing and cocking mechanisms, a trigger, means for moving said firing mechanism in the direction of movement of the breech block mechanism and a distance substantially equal to the displacement of said breech block mechanism, a catch on said firing mechanism cooperating with the breech block mechanism, and means independent of said trigger for locking said firing mechanism in the cocked position.

60 6. An automatic firearm according to claim 5 and characterized by a carrier for said firing and cocking mechanisms, and means for mounting said carrier to be longitudinally displaced with respect to said firearm.

65 7. An automatic firearm according to claim 5, characterized in that the firearm is provided with an opening for the ejection of shells, a carrier for said firing mechanism, and means for slidably mounting said carrier on the firearm whereby in one position it covers and in another position it frees said opening.

70 8. An automatic firearm according to claim 5, characterized in that said means for locking the firing mechanism comprises a movable stop carried by said breech block mechanism, and a stationary stop cooperating therewith mounted on the firearm.

75 9. An automatic firearm according to claim 5, characterized by a pivotal mounting for said catch, and means controlled by the firing mechanism for actuating said catch.

80 10. An automatic firearm according to claim 5, characterized by a pivotal mounting for said catch, a control member for actuating said catch, means controlled by the firing mechanism for operating said control member, and a switching member for single shot and continuous firing cooperating with said last-mentioned means.

85 11. An automatic firearm according to claim 5, characterized by a trough-shaped housing enclosing the firing mechanism and said means for locking it.

90 12. An automatic firearm according to claim 5, characterized by a carrier for said firing mechanism, and a handle on said carrier.

95 13. An automatic firearm according to claim 5, characterized by a carrier for said firing mechanism, and a handle on the rear end of said carrier accessible to the hand the thumb of which operates said trigger.

100 14. An automatic firearm according to claim 5,

characterized by a carrier for said firing mechanism, a handle on the rear end of said carrier accessible to the hand the thumb of which operates said trigger, and a lever for operating said means for locking said firing mechanism accessible to the thumb of said hand.

5. An automatic firearm according to claim 5,

characterized by a carrier for said firing mechanism, means for operating said catch in response to the opening, and means for operating the locking means of the firing mechanism in response to the closing movement of said carrier.
